UNITED STATES PATENT OFFICE.

LEWIS H. BROOME, OF JERSEY CITY, NEW JERSEY.

BOTTLE-STOPPER.

SPECIFICATION forming part of Letters Patent No. 632,006, dated August 29, 1899.

Application filed April 10, 1899. Serial No. 712,380. (No model.)

To all whom it may concern:

Be it known that I, LEWIS H. BROOME, a citizen of the United States, residing at Jersey City, in the county of Hudson and State 5 of New Jersey, have invented an Improvement in Bottle-Stoppers, of which the following is a specification.

Bottles have been made with offsets or shoulders within the mouth upon which a 10 cork has been introduced and held down by a plug, bail-wire, and lever to the connection around the outside of the neck. With aerated water it is found that the pressure causes the liquid to pass through the cork to a greater 15 extent. I prevent this by applying a disk of paper saturated with paraffin or similar wax and resting upon the shoulder between the cork and the liquid, and I combine along with the plug or body a flanged connection 20 to the bail-wire and a layer of rubber between the flange of the connection and the parts of the body, so that the bail-wire as it is pressed in between the body and the connection causes the rubber to be compressed 25 to a greater or less extent, so as to apply a constant pressure and friction of the connection upon the bail-wire, so that the plug or stopper will not be loose to slip endwise upon the bail-wire, but will hold in the normal position 30 under the ordinary circumstances of use and not become displaced.

In the drawings, Figure 1 is a vertical section of the improvement as adapted to use with liquid that is under pressure in the bottle. Fig. 2 is a similar view with a different 35 shape of body. Fig. 3 is a section of the body shown in Fig. 1 at right angles to Fig. 1, and Fig. 4 is a plan view of the body shown in Fig. 3.

The bottle-neck A is provided with a shoulder at 2 around the inner surface, and upon this I place a disk of thick paper 3, prepared with paraffin or similar waterproof wax, and the size of this disk is sufficient to cover the 45 shoulder and rest at its edges against the interior cylindrical part of the mouth of the bottle, and the cork B rests upon the paper 3 and upon the shoulder, and the pressure applied thereto makes a tight joint between the 50 shoulder and the cork and the intervening layer of paper, and the paper prepared with wax intervening between the liquid in the

bottle and the cork prevents such liquid passing into the cork.

The stopper-body C, Figs. 1, 3, and 4, is 55 adapted to rest upon the cork B, so as to hold the same firmly in place, and the upper surface of the body is recessed for the reception of the connection D, and this is adapted to extend up and pass over the bail-wire E, and 60 the base of the connection D is flanged at 4, and a disk of rubber F rests upon the flange 4 and below the portion 5 of the body C, so that the rubber being sprung around the respective parts holds the connection D in position, and when the bail-wire E is forced in beneath the connection, which is shown in 65 Fig. 1 as a hook, and above the surface 6 of the stopper-body the rubber F is slightly compressed, so that this rubber F acts constantly 70 to keep the bail-wire E against the surface 6, and thereby apply sufficient friction to prevent the stopper sliding endwise of the bail-wire in order that the stopper may remain approximately in the proper position when the 75 bottle is uncorked.

The same parts as those before described are represented in Fig. 2; but the stopper-body C' is shaped differently from the stopper-body C, and the rubber F' is introduced 80 between the flange 14 of the connection D' and the shoulder 15 of the body C', so that the rubber F' is compressed as the bail-wire E is pressed in between the connection D' and the surface 16 of the body C'. In both instances the rubber performs the same duty of applying a friction between the connection, the bail-wire, and the surface of the stopper, so as to prevent the stopper slipping endwise upon the bail-wire. 90

In Fig. 2 the body C' is represented as sufficiently long to extend above the bail E, there being a hole across through the body for the passage of the bail, and I remark that the form of stopper represented in Fig. 1 is better adapted to aerated waters or liquids introduced under pressure into the bottle, because the outer edges of the elastic washer F can form a tight joint in the filling apparatus and above the inlet for the liquid, so that the stopper-body, the cork, and the disk of paper can be inserted into the filling apparatus before the bottle is filled with the liquid and then forced down through that filling appa- 95 100

ratus into the mouth of the bottle and held there until the bottle is removed and the bail-wire swung up into place beneath the hook of the connection for holding the stopper in position.

It is to be understood that the plunger ordinarily made use of in bottle-filling apparatus is to be constructed with reference to giving opportunity for swinging up the bail-wire 10 E into position before the sustaining-power, acting upon the plunger, is removed, the pressure at that time being supported by the bail-wire and the lever connection to the band around the bottle-neck, as usual.

15 I claim as my invention—

1. The combination with the bottle having an internal shoulder within the neck, a stopper-body and means for pressing the same into the neck, of a cork plug independent of 20 the stopper-body and coming between the same and the shoulder and a disk of water-

proof paper against the under side of the separate cork to render the parts waterproof, substantially as set forth.

2. The combination with the bail-wire and 25 the bottle-stopper body having a recess, of a flanged connection with the flange within the said recess and a layer of rubber between such flange and the stopper-body, whereby the flanged connection is allowed to yield by 30 the rubber as the bail-wire is passed between the connection and the stopper-body so as to apply a pressure upon the bail-wire and prevent the stopper sliding upon said bail-wire under the ordinary circumstances of use, substantially as set forth.

Signed by me this 3d day of April, 1899.

L. H. BROOME.
